UNITED STATES PATENT OFFICE.

FELIX EBERHART, OF NEWARK, NEW JERSEY, ASSIGNOR TO AMERICAN CAN COMPANY,
OF NEW YORK, N. Y., A CORPORATION OF NEW JERSEY.

METALLIC LABEL.

1,144,534.

Specification of Letters Patent. Patented June 29, 1915.

Application filed August 14, 1912. Serial No. 714,946.

To all whom it may concern:

Be it known that I, FELIX EBERHART, a citizen of the United States, residing in Newark, in the county of Essex and State of New Jersey, have invented a new and useful Improvement in Metallic Labels, of which the following is a specification.

This invention relates to an improvement in metallic labels suitable for application to filled cans, and more particularly to filled sardine cans having countersunk covers, and the invention consists in a countersunk sheet metal label extending from rim to rim of the countersunk can head and secured at said 15 rim to the can by bending the material of the label, as will be more particularly set forth and claimed.

In the accompanying drawing which forms a part of this specification, Figure 1 is a perspective view of the ordinary sardine can provided with the improved label. Fig. 2 is a section taken diagonally through Fig. 1 on the line 2—2 of said figure. Fig. 3 is a perspective view of the label before the 25 same is applied.

This invention presents a label which may be made separately from the can, may be printed or lithographed with whatever form of printed matter is desired, and may be applied to the can after the same has been filled and sealed. The advantages of this method of labeling sardine cans over the old and well known methods of lithographing the cover or body of the can itself or soldering a brass label upon the can body, consists 35 in the fact that it enables the manufacturer of the cans to keep large quantities of cans in stock against sudden orders, since the labels for different users, not being upon 40 the cans themselves, may be rapidly made up as required in each instance, or made up in advance and kept on hand by the particular user himself. The use of this added label also does away with danger of mutilation 45 and scratching of the decorated surface and the soiling of the same with oil and dirt which may happen during the filling and processing of the can. A further advantage 50 of this particular kind of label, as compared with the old form of label soldered upon the can, is that it may be applied to the filled can without the use of solder and secured by a simple tucking operation, bending the material of the label itself beneath the shoulder 55 of the seam between the can head and can

body; and when this label extends diagonally across the can, as it may, this tucking attachment of it to the can body operates to secure it against any sliding, as well as vertical removal.

In the accompanying drawing, A represents an ordinary filled sardine can, of which B is the cover and C the interfolded seam between the body and the cover. This cover, it will be noted, is countersunk, and the seam 65 forms a shoulder D extending around the rim of the can.

E is the label made of a strip of sheet metal and countersunk to conform to the contour of the can cover, so that at each end of the label is a groove F, the outer wall G of which extends down far enough to be turned under the shoulder D. The grooves F, F, one at each end, of the label are made to fit over the rim of the can body and cover, 70 as indicated at Fig. 1, and preferably are made to fit over the diagonally opposite corners of the can as shown in that figure. This preferred construction gives a curved form to the groove F, so that when the label 75 is applied, and the depending flange G tucked under the shoulder D, as indicated in section at Fig. 2, the label is secured both against upward removal and turning or sliding, the latter movement being prevented by 80 the form of the can body itself, as will be readily understood. The sardine can being four sided with rounded corners, causes the label when applied thus diagonally, to be locked firmly in place. In the manufacture 85 of these labels, the blanks may be first cut out, the surface lithographed, and the ends stamped up in the form indicated in Fig. 3. In this condition they may be kept in stock until needed, and applied to the cans by any 90 ordinary tucking machine.

I claim:—

1. A sheet metal label for cans consisting of an elongated sheet of metal having its body portion intermediate of the ends adapted to lie across the head of the closed can, and formed at each end to be bent around and locked with the upstanding and outstanding seam which unites the can head with the can body, such formation consisting 100 of an upwardly bent portion adapted to lie against the inner side of said seam, an outwardly extending portion adapted to lie over the top of said seam and a downwardly extending portion or wall which is adapted 105 110

to be bent under the bottom of the outstanding seam of the can.

2. The sheet metal label for cans formed with a countersunk face, grooved ends; and an outer depending flange which may be tucked under the shoulder of the seam between the can body and can head, said label

being formed and grooved to fit diagonally across the countersunk face of a four sided, round cornered sardine can.

FELIX EBERHART.
